Fig. 3.

Fig. 5.

Fig. 6.

FIG. 1 is a perspective view of the circuit breaker cap embodying our new design, viewed generally from the top and one side thereof;

FIG. 2 is a side elevation of the circuit breaker cap illustrated in FIG. 1 and shows the right hand side as viewed in FIG. 1, the opposite side being substantially a mirror image thereof, this view and the subsequent ones being at a larger scale than FIG. 1;

FIG. 3 is a top plan view thereof;

FIG. 4 is a bottom plan view thereof;

FIG. 5 is a cross-sectional view thereof taken along the line 5—5 in FIG. 4; and

FIG. 6 is a cross-sectional view thereof taken along the line 6—6 in FIG. 3.

The dominant features of our new design are shown in solid lines in the drawing.

We claim:

The ornamental design for a circuit breaker cap, as shown and described.
